PRESS CONTROL

Walter Ernst and Philip J. Lindner, Mount Gil-
ead, Ohio, assignors to The Hydraulic Devel-
opment Corporation Inc., Wilmington, Del., a
corporation of Delaware

Application January 18, 1941, Serial No. 375,030

13 Claims. (Cl. 103—38)

This invention relates to hydraulic machinery, and in particular to hydraulic pumps having a flow-control member and servomotor means for controlling the position of said flow-control member. Although not limited to the use in connection with presses, the present invention is of particular advantage in connection with hydraulic presses in which provision is made for slowing down the movement of the press platen shortly before the work piece is engaged by the die connected with said platen.

Presses of this type, as heretofore known, have the drawback that if for some reason it has been omitted to insert a work piece in the press, so that no resistance is encountered by the press platen, the press will immediately speed up again to full speed. This may result in injuries to the operator and also completely ruin the dies.

In our copending application 357,444 filed September 19, 1940, there is described a press which overcomes the above drawback by allowing the platen to advance in its pressing direction only at a reduced speed if the platen, after having passed its normal work piece engaging position, does not encounter a resistance of a predetermined magnitude. In such instances the platen may very slowly move downwardly until it engages the press bed and automatically return to its initial position, or the driving connection for the pump which supplies fluid pressure to the press ram may be interrupted, thereby stopping the pump delivery and the movement of the platen. However, even in the last mentioned case, it might be that the period of time for stopping the press may exceed a minimum time for meeting an emergency.

Accordingly, it is an object of the present invention to provide means which, when used in connection with a press of the above character, may cause the platen, at any time during its working stroke, to stop virtually instantaneously.

It is a further object of the invention to provide servomotor means for a variable delivery pump which at any desired time during the working stroke of the pump, may cause the latter instantaneously to shift to neutral or no-delivery position.

A still further object of the invention consists in the provision of servomotor means of the type set forth in the preceding paragraph, in which the shifting of the variable delivery pump to neutral position is effected by fluid means.

It is still another object of the invention to provide a variable delivery pump comprising servomotor means in which, at a desired time, yield-

ing means may be made effective for shifting said pump instantaneously to neutral or no-delivery position, while latching means will maintain said pump in said neutral position.

These and other objects and advantages of the invention will appear more clearly from the following specification in connection with the accompanying drawings, in which:

Figure 1 diagrammatically illustrates a first embodiment of the invention.

Figure 2 is a simplified wiring diagram for the electric system controlling the device of Figure 1.

Figure 3 is a second embodiment of the invention, and

Figure 4 illustrates, in a manner similar to that of Figure 2, the electric control circuit for the embodiment of Figure 3.

General arrangement

According to the present invention the flow-control member of a variable delivery pump supplying pressure fluid to the press platen is operatively connected with a cylinder-piston-assembly which, at a desired time during the working stroke of the press platen, may be controlled so that it moves the flow-control member of said variable delivery pump to no-delivery position and maintains the same in said position for a desired length of time.

According to a first embodiment of the invention, a variable delivery pump is shiftable into forward delivery position by a fluid operable cylinder-piston-assembly which is operatively connected with a second cylinder-piston-assembly adapted to counteract said first mentioned cylinder-piston-assembly for moving the pump to neutral or no-delivery position.

According to a second embodiment of the invention, a reversible variable delivery pump is provided for supplying pressure fluid to the press platen to advance or retract the latter. Yielding means associated with the pump and constantly urging the same to retraction stroke position may, whenever desired, be counteracted by a fluid operable cylinder-piston-assembly for moving the pump into forward stroke position, while a fluid operable latching member may be made operable to stop the flow-control member of the pump in neutral or no-delivery position when said yielding means is made effective for shifting the pump to its retraction stroke position.

*Structural arrangement of first embodiment
(Figures 1 and 2)*

Referring now to Figure 1 in detail, the press shown therein comprises a press head 1 includ-

ing a press cylinder bore 2 which has reciprocably mounted therein a double-acting press piston 3 supporting the press platen 4.

The upper portion of the press cylinder bore 2 communicates, by means of a conduit 5, with one side of a reversible variable delivery pump 6. The other side of the reversible variable delivery pump 6 communicates, by means of conduit 1, with the lower portion of the press cylinder bore 2.

Connected with the conduit 5 is a low pressure responsive or tonnage control valve 8 adapted to communicate with a fluid reservoir or surge tank 9 arranged on top of the press head 1, and adapted to supply pressure fluid to the upper portion of the cylinder bore 2 by means of a surge valve 10.

The surge valve 10 is adapted to communicate through a conduit 11 with the conduit 12 communicating on one hand with a check valve 13 and on the other hand with a main cylinder relief and pump by-pass valve 14. The surge valve 10 and main cylinder relief and pump by-pass valve 14 do not form a part of the present invention and for a more detailed description thereof reference may be had to U. S. Patent

No. 2,193,248 to Ernst and U. S. patent application Serial No. 286,063, filed July 24, 1939, likewise to Ernst.

The purpose of the surge valve 10 merely consists in pre-filling the proper portion of the cylinder bore 2 when the press piston is moved downwardly by gravity, whereas the main cylinder relief and pump by-pass valve 14 facilitates the reversal of the movement of the press platen at the end of its working stroke.

Also communicating with the conduit 5 is a high pressure tonnage control valve 15 which, when actuated, effects the reversal of the movement of the press platen of the variable delivery pump 6, thereby causing the platen to effect its retraction stroke.

The pressing platen 4 is adapted to actuate a switch 16 which is electrically connected with a solenoid 17 adapted to actuate a slow-down valve, generally designated 18.

The slow-down valve 18 comprises a cylinder 19 having reciprocably mounted therein a piston 20 and communicating, by means of a conduit 21, with a conduit 22 leading to a fluid pressure source 23. Any kind of fluid pressure source may be used in this connection, for instance a tank filled with compressed air or a fluid pressure creating pump. Arranged in the cylinder 19 is a strong spring 24 which continuously urges the piston 20 to its lowermost position and is adapted to counteract fluid pressure conveyed from the fluid pressure source 23 through conduits 22 and 21 to the lower surface of the piston 20.

The conduit 21 also communicates with a conduit 25 leading to a control valve, generally designated 26. The control valve 26 comprises a cylinder 27 having reciprocably mounted therein a piston 28, the movement of which is controlled by a solenoid 29.

Also provided in the cylinder 27 is a spring 30 similar to the spring 24 of valve 18. The spring 30 continuously urges the piston 28 to its lowermost position and is adapted to counteract fluid pressure conveyed from the fluid source 23 through conduits 22 and 25 to the lower surface of the piston 28.

Communicating with conduits 24 and 25 and the conduit 22 is a conduit 31 which leads to an emergency valve 32. The emergency valve 32 is, in its construction, similar to that of the control valve 26 and slow-down valve 18 and comprises a cylinder 33 having reciprocably mounted therein a piston 34, the movement of which is controlled by a solenoid 35. A strong spring 36 acts upon the upper surface of the piston 34 and is adapted to move the piston 34 to its lowermost position against the action of fluid pressure conveyed from the fluid source 23 through the conduits 22 and 31 through the lower surface of the piston 34.

Each of the valves 18, 26 and 32 has, at its upper portion, a bleeder opening 37, 38 and 39 respectively.

The cylinder 19 of the slow-down valve 18 furthermore communicates through a conduit 40 with the port 41 at one end of a cylinder-piston-assembly generally designated 42. The opposite end of the cylinder-piston-assembly 42 comprises a port 43 communicating through a check valve 44 and a conduit 45 with the cylinder 27 of the control valve 26. The port 41 is provided in a closure member 46 connected in any convenient manner, for instance by screws 47, with a cylinder 48 having a bore 49 with a bleeder opening 50 therein.

Reciprocably mounted in the cylinder bore 49 is a piston 51 mounted on the smaller portion 52 of a shaft or push rod 53. The bottom of the cylinder 48 has a bore 54 through which passes the shaft 53 and in order to prevent leakage along the shaft 53 a sealing member 55 is provided in the bore 54 and is enclosed in said opening by a disc 56. The bottom of the cylinder 48 is connected in any convenient manner, for instance by screws 51, with a cylinder 58 having a larger bore 59 and a smaller bore 60.

Reciprocably mounted in the larger bore 59 is a piston 61 having a bore 62 through which the shaft 53 slidably passes. When the piston 61 is in its extreme right-hand position with regard to Figure 1, it abuts the shoulder 63 of the cylinder 48, whereas in its left-hand position it abuts a shoulder 64. Adjacent the shoulder 64 is provided a bleeder opening 65. The space 66 between the piston 61 and the disc 56 communicates with a passage 67 which in its turn communicates through the conduit 68 with the cylinder 33 of the emergency valve 32.

The piston 61 has a U-shaped recess 69 adapted to be engaged by a correspondingly shaped portion of a piston 70 reciprocably mounted in the bore 60 of the cylinder 32.

The piston 70 which is movable independently of the pistons 61 and 51 is provided with one or more L-shaped bores 71 adapted to allow fluid entrapped between the pistons 61 and 70 to escape into the bore 59.

The piston 70 has threadedly connected thereto a shaft 72 passing through the closed end of the bore 60. To prevent leakage between the cylinder bore 60 and the shaft 72, a sealing member 73 is provided which is enclosed by a nut 74. The end of the cylinder bore 60 adjacent the port 43 is provided with an exhaust bore 75 which is spaced a short distance from the extreme end of the bore 60 so that the piston 70 covers the exhaust bore 75 before the piston 70 abuts the bottom portion 76 of the bore 60.

To prevent fluid from being completely entrapped between the cylinder bottom portion 76 and the piston 70 when the latter in its movement toward the left with regard to Figure 1 has just closed the exhaust bore 75, choke bores 77 and 78 are provided which are plugged toward

the outside but communicate with each other and with the exhaust bore 75 which in its turn communicates through conduit 79 with the conduit 45. In this way the fluid entrapped between the cylinder bottom portion 76 and piston 70, when the latter has covered the exhaust bore 75, can escape into the conduit 45 only through the choke bores 77 and 78, thereby cushioning and slowing down the last portion of the movement of the piston 70 toward the cylinder bottom 76. A direct escape of said entrapped fluid through the port 43 into the conduit 45 is prevented by the check valve 44 which opens only toward the port 43 and is arranged between the latter and the point where the conduit 78 leads into the conduit 45.

Threadedly connected to the shaft 72 and secured in its position by a nut 80 is a yoke 81 connected by a pivot 82 with a bell-crank lever 83. The bellcrank lever 83 is shiftable about a pivot 84 which pivotally connects the bellcrank lever 83 with a link 85 pivotally connected to a lug 86 forming a part of the servomotor cylinder 87 pertaining to the reversible variable delivery pump 6.

Also pivotally connected to the bellcrank lever 83 is a shift rod 81 adapted to shift the shift ring (not shown) of the variable delivery pump 6 so as to move the pump selectively into forward stroke, retraction stroke, or no-delivery position.

A spring 92 abuts a collar 93 on the shift rod 81 and continuously urges the shift rod 81 toward the left with regard to Figure 1, so that the pump 6 is moved to its retraction stroke position. It will be clear from the drawings that when the spring 92 moves the shift rod 81 toward the left, the arm 94 of the bellcrank lever 83 will, by means of the shaft 72, shift the piston 70 toward the left. Reversible variable delivery pumps of the above character are well known to those skilled in the art, and an assembly of the said type of pumps is disclosed, for instance, in the U. S. Patent No. 2,039,893 to Ernst.

The free arm 95 has a rounded portion 96 engaging a collar 97 provided in the uppermost portion of the push rod 98. The push rod 98 has adjustably mounted thereon a collar 99 engaging with its upper portion one end of a spring 100, the other end of which abuts a stationary lug 101, which guides the push rod 98 in its reciprocating movement. The spring 100 urges the push rod 98 downwardly. Also adjustably mounted on the push rod 98 is a collar 102 adapted to be engaged by the arm 103 connected to the platen 4. Lifting movement of the platen 4 will, therefore, lift the push rod 98 as soon as the arm 103 engages the collar 102.

The electric control system pertaining to the solenoids 17, 29 and 35 of the slow-down valve, control valve and emergency valve respectively, and also comprising the tonnage control valves 8 and 15, is shown in a simplified diagram in Figure 2. In this diagram the numerals 104 and 105 designate the main supply lines.

The main supply line 104 is connected with a line 106 leading to a terminal 107 which is adapted to be connected with the terminal 108 by operation of the normally open push button switch 109. The terminal 106 is connected to the line 110 leading to one end of the solenoid 111 controlling the contactor blades 112 and 113. The other end of the solenoid 111 is connected with the line 114 leading to the main supply line 105.

When the solenoid 111 is energized, its con-

tactor blade 112 bridges its adjacent terminals, of which the terminal 115 is connected through line 116 with the main supply line 104, while the terminal 115' is connected to a terminal 117 of the normally closed high pressure tonnage control valve 16. The other terminal 118 of the high pressure tonnage control valve 16 is connected, by means of line 119, with the line 110. The contactor blade 113 is adapted to effect communication between the line 120 and the line 121, which latter leads to the control valve solenoid 29 connected in its turn by line 122 with the main supply line 105.

Also connected with the main supply line 104 is a line 123 leading to a terminal of a platen operable switch 16, the other terminal of which is connected by line 124 with one end of a solenoid 125. The other end of the solenoid 125 communicates, by means of line 126, with the main supply line 105. The solenoid 125 controls the operation of the contactor blades 127 and 128.

The blade 121 is adapted to effect communication between the line 129 connected with the main supply line 104 and the line 130 leading to one terminal of the normally closed low pressure tonnage control valve 8, the other terminal of which is connected through line 131 to the line 124. Closure of contactor blade 128 effects communication of line 132 connected to the main supply line 104 with line 133 leading to one end of the slow-down valve solenoid 17, the other end of which communicates through line 134 with the main supply line 105.

Further communicating with the main supply line 104 is a line 135 leading to a terminal 136 which is adapted to be connected with the terminal 137 by closure of the normally open emergency switch 138. Connected with the terminal 137 is a line 140 which is normally connected with the line 139 by means of the normally closed reset switch 140. The line 139 leads to one end of a solenoid 141, the other end of which communicates through line 142 with the main supply line 105. Connected with the line 160 is a line 143 which, by closure of the contactor blade 144 pertaining to solenoid 141, is adapted to be connected with the line 145 leading to the main supply line 104. A second contactor blade 146 pertaining to the solenoid 141 effects, when closed, communication between the line 147 connected to the main supply line 104 with the line 148 leading to one end of the emergency valve solenoid 35, the other end of which is connected to a line 149 leading to the main supply line 105.

Operation of first embodiment

Supposing that the press ram 3 is in the position shown in Figure 1, while the pistons 70, 61 and 51 are in their extreme left-hand position, and assuming further that the pump 6 is rotated by a driving motor, to start a working cycle, the operator actuates the push button switch 109 so as temporarily to bridge the terminals 107 and 108.

Current will then flow from the main supply line 104 through line 106, switch 109, line 110, solenoid 111 and line 114 to the main supply line 105. Energization of the solenoid 111 causes switch blade 112 to bridge the terminals 115 and 115', thereby establishing a holding circuit for the solenoid 111, which holding circuit comprises the main supply line 104, line 116, contactor blade 112, high pressure tonnage control valve

15, line 119, solenoid 111 and line 114 connected to the main supply line 105.

Energization of the solenoid 111 also causes the contactor blade 113 to effect communication between the lines 120 and 121 so that current flows from the main supply line 104 through line 120, contactor blade 113, line 121, control valve solenoid 29 and line 122 to the main supply line 105. In this way the control valve solenoid 29 is energized, which then moves the piston 28 upwardly against the thrust of the spring 30. As a result thereof, pressure fluid from the pressure fluid source 23 passes through conduits 22, 25 and 45 through the check valve 44 into the port 43. From here the fluid flows into the cylinder bore 60 where it acts upon the piston 70 so as to move the latter toward the right. As soon as the piston 70 engages the piston 61, it carries the latter along in its rightward movement. When the piston 70 during its rightward movement engages the shaft 53, also the latter is moved toward the right, thereby shifting the piston 51 likewise toward the right. When the pistons 70, 61 and 51 have reached the position shown in Figure 1 they come to a standstill.

Since rightward movement of the piston 70 pulls the shaft 72 toward the right, bell-crank lever 83 will be shifted so that the shift rod 91 likewise moves toward the right, thereby compressing the spring 92. Consequently, when the piston 70 has reached its extreme right-hand position, the shift rod 91 has shifted the pump 6 to full stroke forward delivery position. The pump 6 now delivers fluid through conduit 5 into the upper portion of the cylinder bore 2, while the ram 3 moves downwardly by gravity and, furthermore, fluid from the fluid tank 9 passes through the now open surge valve 10 into the upper portion of the cylinder bore 2.

As soon as the press platen 4 approaches the position where it normally engages a work piece, the platen 4 actuates the switch 16 so as to close the latter. As a result thereof, current flows from the main supply line 104 through the now closed switch 16, the line 124, solenoid 125 and line 126 to the main supply line 105. The solenoid 125 is therefore energized, thereby causing the contactor blade 127 to close the holding circuit for solenoid 125, which holding circuit comprises main supply line 104, line 129, contactor blade 127, line 130, low pressure tonnage control valve 8, line 131, solenoid 125, line 126 and main supply line 105.

Energization of the solenoid 125 also causes the contactor blade 128 to close the circuit comprising the main supply line 104, line 132, blade 128, line 133, slow-down valve solenoid 17, line 134 and main supply line 105.

Energization of the slow-down valve solenoid 17 causes upward movement of the piston 28 against the thrust of the spring 24 so that pressure fluid from the pressure fluid source 23 is conveyed through conduits 21, 22 and 40 to the port 41. From here the fluid flows past the piston 51 and inasmuch as the effective piston area of the piston 51 is larger than the effective piston area of the piston 70 upon which the pressure fluid admitted through the port 43 acts, the piston 51 moves toward the left, thereby also moving the shaft 53 toward the left which in its turn moves the piston 70 toward the left. The piston 51 in its leftward movement comes to a standstill when it abuts the left end of the cylinder bore 48.

The leftward movement of the piston 51 and, 75

thereby, of the piston 70 is conveyed through shaft 72 and bellcrank lever 83 to the shift rod 91 so that when the pistons 51 and 70 come to a standstill, the shift rod 91 has moved the pump 6 to a restricted forward delivery position in which only a small quantity of fluid is delivered by the pump 6 to the upper portion of the press cylinder bore 2. The downward movement of the press piston 3 is, therefore, slowed down in accordance with the rate at which the pump withdraws fluid from the retraction side of the press piston 3. Although the platen 4, after a very short time, disengages the switch 16 so that the latter is open again, this will not affect the slow-down movement due to the fact that the solenoid 125 remains energized, in view of the holding circuit established by the closure of the blade 127, as mentioned above.

The downward movement of the press piston 3 therefore continues with reduced speed until the platen 4 comes to a standstill by engaging a die on the press bed, unless a work piece was placed on the press bed and engaged by the die connected to the platen. If, during the downward movement of the press piston 3 the die connected to the platen engages a work piece, pressure starts to build up in the upper portion of the press cylinder 2, and as soon as a minimum pressure is attained the surge valve 10 closes, whereas the low pressure tonnage control valve 8 opens. Opening of the low pressure tonnage control valve 8 breaks the holding circuit for the solenoid 125 so that the blade 128 interrupts the energizing circuit for the slow-down valve solenoid 17.

As a result of the deenergization of the solenoid 17, the spring 24 returns the piston 28 to its lowest position, thereby interrupting communication between the fluid pressure source 23 and the conduit 40, while enabling communication between the conduit 40 and the bleeder opening 37 so that the fluid past the piston 51 may escape through the bleeder opening 37 to an exhaust. Since, on the other hand, the cylinder bore 60 through conduit 45, the control valve 26 and conduits 25 and 22 still communicates with the pressure fluid source 23, the piston 70 is again moved toward its extreme right-hand position, thereby returning the pump 6 to full stroke forward position. As a result thereof, the downward movement of the press piston 3 is speeded up and the actual pressing operation is effected with high speed.

As soon as the pressing operation is finished and a predetermined high pressure built up in the upper portion of the cylinder bore 2, the high pressure tonnage control valve 15 is actuated by the said high pressure so as to break the holding circuit for the solenoid 111. Consequently, the contactor blades 112 and 113 return to their open position so that the control valve solenoid 29 is deenergized and the control valve piston 28 returns to its lowermost position. In this position the communication between the fluid pressure source 23 and the conduit 45 is interrupted, while the conduit 45 now communicates with the bleeder opening 38. The spring 92 in the servomotor cylinder 87 is, therefore, not opposed by pressure acting upon the piston 70 so that the spring 92 will now actuate the shift rod 91 so as to move the pump 6 to full stroke retraction position. When carrying out this movement, the lever 83 shifts the shaft 72 and the piston 70 connected thereto toward the left.

Due to the provision of the small choke bores

77 and 78, a throttling action is produced at the point of reversal of the variable delivery pump so that a smooth initiation of the retraction stroke is obtained. The pump 6 now delivers pressure fluid through conduit 7 into the lower portion of the cylinder bore 2, thereby moving the platen upwardly until the platen arm 103 engages the collar 102, thereby lifting the push rod 98 which in its turn engages the arm 95 of the bellcrank lever 83 at the end of the retraction stroke of the platen and shifts the lever 85 so that the shift rod 91 moves the pump 6 to neutral position. The pump is then ready for a new cycle.

Supposing now that during the downward stroke of the press platen 4 an emergency occurs, for instance that a work piece while being pressed starts cracking, and that it is desired instantaneously to stop the press. As mentioned above, during the downward stroke of the press platen 4 and engagement of a work piece by said platen, the solenoid 111 and, consequently, also the solenoid 29 of the control valve 26 is energized so that pressure fluid from the fluid source 23 has moved the piston 70 to its extreme right-hand position and has placed the pump 6 on full stroke forward delivery position against the thrust of the spring 92.

In order to stop the press platen when an emergency occurs during the downward stroke of said platen, the operator actuates the emergency switch 138, thereby closing the circuit comprising the main supply line 104, line 135, line 160, reset switch 140, line 139, solenoid 141, line 142 and main supply line 105.

Energization of the solenoid 141 causes contactor switch blade 144 to close, thereby establishing a holding circuit for the solenoid 141. This holding circuit comprises the main supply line 104, line 145, contactor blade 144, line 143, reset switch 140, line 139, solenoid 141, line 142 and main supply line 105. Energization of the solenoid 141 also causes the blade 146 to effect communication between the line 147 and the line 148, thereby closing the circuit through the emergency valve solenoid 35.

Energization of the solenoid 35 causes lifting movement of the emergency valve piston 34 against the thrust of spring 36, thereby establishing communication between conduits 31 and 68. As a result thereof, pressure fluid is conveyed from the fluid source 23 through conduit 68 into the passage 67 and the space 66. Here the pressure fluid acts upon the piston 61 and, inasmuch as the effective piston area of the piston 61 is greater than the effective piston area of the piston 70 acted upon by pressure fluid admitted through conduit 45, the piston 61 moves toward the left, thereby also shifting the piston 70 and the shaft 72 toward the left.

When the piston 61 abuts the shoulder 64, the pistons 61 and 70 come to a standstill and, at this time, the piston shaft, and thereby the shift rod 91, has been shifted to such an extent that the pump 6 is in neutral or no-delivery position. Since, in this position, no fluid is withdrawn from below the press piston 3, no further downward movement of the platen 4 can occur. In other words, the press platen has come to a standstill.

If desired, the shoulder 64 may be located so that the pump 6 is moved slightly beyond neutral position so that, if the emergency switch 138 is actuated, a very slow retraction stroke of the platen 4 is started.

Second embodiment Figures 3 and 4

Referring now to Figure 3 illustrating the second embodiment of the invention, only the pump with the control valve, emergency valve, slow-down valve and the control cylinder-piston-assembly is shown, since the connection of the structure illustrated in Figure 3 with the press assembly is the same as that illustrated in Figure 1. Inasmuch as the variable delivery pump of Figure 3 and the structure of the control valve, emergency valve and slow-down valve fully corresponds to that described in connection with Figure 1, these members have been provided with the same reference numerals as the corresponding members in Figure 1, however, with the additional letter *a*.

As will be seen from Figure 3, the control cylinder-piston-assembly 150 shown therein has omitted the cylinder 48 of Figure 1 and has the closure member 46a connected directly to the cylinder 58a. Furthermore, the piston 51 and shaft 53 of the embodiment of Figure 1 have been omitted.

The cylinder 58a is provided with a boss 151 comprising a cylinder bore 152 in which is reciprocably mounted a piston 153 carrying a latch 154. Arranged between the top of the cylinder bore 152 and the upper surface of the piston 153 is a spring 155 which constantly urges the piston 153 to its lowermost position.

The upper end of the cylinder bore 152 communicates through a conduit 156 with the conduit 79a which in its turn communicates with the conduit 45a. The lower end of the cylinder bore 152 communicates through a conduit 68a with the upper portion of the emergency valve cylinder 33a.

The electrical control system pertaining to Figure 3 is shown in Figure 4 and substantially corresponds to that of Figure 2. The corresponding parts have, therefore, been designated with the same reference numerals, however, with the additional letter *a*. The electrical circuit of Figure 4 differs from that in Figure 2 substantially in the arrangement of the holding circuit for the solenoid controlling the energization of the control valve.

As will be seen from Figure 4, the solenoid 141a controls a contactor with three blades 144a, 146a and 151. While the normally open blades 144a and 146a correspond to the blades 144 and 146 of Figure 2, the third blade 151 is normally in closed position, in which it connects the line 119a with a line 158 which in its turn is connected to line 110a.

Operation of second embodiment

The operation of the arrangement of Figures 3 and 4 is similar to that of Figures 1 and 2.

Supposing that the piston 70a is in its extreme left-hand position and that also a piston 51a, which in its function corresponds to the piston 51 but in its shape to the piston 61, is likewise in its extreme left-hand position and that it is now desired to carry out a working cycle, the operator first starts the pump 6a and then actuates the starting switch 109a. Actuation of the switch 109a closes a circuit comprising the main supply line 104a, line 106a, line 110a, solenoid 111a, line 114a and main supply line 105a.

Energization of the solenoid 111a causes contactor blade 112a to establish a holding circuit for the solenoid 111a, which holding circuit comprises the main supply line 104a, line 116a, blade 112a, high pressure tonnage control valve 15a,

line 119a, contactor blade 157, line 158, solenoid 111a, line 114a and main supply line 105a.

Energization of the solenoid 111a also causes blade 113a to connect the lines 120a and 121a, thereby energizing the control valve solenoid 29a. As a result thereof, the control valve piston 28a is lifted against the thrust of the spring 30a, thereby establishing communication between the conduits 25a and 45a so that pressure fluid from the fluid source 23a is conveyed through conduits 22a, 25a and 45a into the cylinder bore 60a past the piston 70a. This pressure fluid moves the piston 70a toward the right, thereby also moving the piston 51a toward the right. When piston 51a abuts the closure member 46a, both pistons 51a and 70a come to a standstill. The rightward movement of the piston 70a causes the shift rod 91a, in the same manner as described in connection with Figure 2, to move the pump 6a to full stroke forward delivery position.

When the press platen approaches its normal work piece engaging position, it closes the switch 16a, thereby connecting the lines 123a and 124a and energizes the solenoid 125a in the manner described above.

Energization of the solenoid 125a causes the blades 127a and 128a to bridge the adjacent terminals pertaining thereto so that a holding circuit for solenoid 125a is established and the slow-down valve solenoid 17a is energized. Consequently, slow-down valve piston 20a is lifted so that pressure fluid from the pressure fluid source 23a is conveyed through lines 22a, 21a and 40a past the piston 51a. Inasmuch as the effective area of piston 51a is greater than the effective area of piston 70a, the piston 51a moves toward the left until it abuts the left-hand bottom surface 64a of the cylinder bore 59a. Leftward movement of the piston 51a also causes leftward movement of the piston 70a, which latter movement causes the shift rod 91a to move the pump 6a to a restricted forward delivery position. The press platen, therefore, advances now only slowly.

If a work piece has been inserted previously, pressure will build up in the press as soon as the work piece is engaged so that the low pressure tonnage control valve 8a will interrupt communication between the lines 131a and 130a, thereby breaking the holding circuit for solenoid 125a. As a result, the blade 128a opens and the slow-down valve solenoid 17a is deenergized so that the slow-down valve piston 20a is returned to its lowermost position, while communication between the conduit 40a and the bleeder opening 31a is established. Fluid pressure acting upon piston 70a therefore returns piston 70a to its previous extreme right-hand position, as a result of which the pump 6a is restored to full stroke forward delivery position. The further operation of the press is the same as described in connection with Figures 1 and 2.

Supposing now that during the advancing stroke of the press platen it is desired to stop the same instantaneously. To this end, the operator closes the emergency switch 138a, thereby establishing a holding circuit comprising the main supply line 104a, line 135a, the switch 138a, reset switch 140a, line 139a, solenoid 141a, line 142a and main supply line 105a.

Energization of the solenoid 141a causes the blades 144a and 146a to close and the blade 157 to open. Consequently, a holding circuit for solenoid 141a is established comprising main supply line 104a, line 145a, blade 144a, line 148a,

line 160a, reset switch 140a, line 139a, solenoid 141a, line 142a and main supply line 105a. The energizing circuit for the solenoid 35a is closed, which circuit comprises main supply line 104a, line 141a, blade 146a, line 148a, solenoid 35a, line 149a and main supply line 105a.

Energization of the emergency valve solenoid 35a lifts the emergency valve piston 34a to its uppermost position, thereby effecting communication between the conduits 31a and 68a. Pressure fluid from the fluid source 23a is, therefore, conveyed through conduits 22a, 31a and 68a past the stop piston 153 which is pushed forward against the action of the spring 155 so that the latch 154 enters the cylinder bore 60a.

Opening of the blade 157 interrupts communication between the lines 119a and 158, thereby breaking the energizing circuit for the solenoid 111a. As a result thereof, the control valve 20 solenoid 29a is deenergized so that the control valve piston 28a is returned to its lowermost position and the connection between the lines 25a and 45a is interrupted, while communication between the line 45a and bleeder opening 38a is established. Inasmuch as the spring 92a urging the pump 6a to full stroke retraction position is now no more opposed by fluid pressure acting upon piston 70a, it will shift the bellcrank lever 83a so as to move the piston 70a toward the left; however, as soon as the piston 70a abuts the latch 154 it is stopped. In this position the pump 6a is in no-delivery position so that the press platen comes to a standstill.

To reset the device, the reset switch 140a is momentarily opened, thereby breaking the energizing circuit for the solenoid 141a and, consequently, also deenergizes the emergency valve solenoid 35a so that the emergency valve piston 34a is returned to its lowermost position by the spring 36a in the emergency valve 32a. Consequently, communication between the conduits 31a and 68a is interrupted, while communication between the conduit 68a and the bleeder opening 38a is established. The fluid past the stop piston 153 therefore escapes through the bleeder opening 38a, and the spring 155 returns the piston 153 to its lowermost position so that the piston 70a is unlocked. The spring 92a pertaining to the servomotor cylinder 87a may then shift the pump to retraction stroke position for retracting the press platen.

It will be understood that we desire to comprehend within our invention such modifications as come within the scope of the claims and the invention.

Having thus fully described our invention what we claim as new and desire to secure by Letters Patent, is:

1. In combination with the flow-control member of a reversible variable delivery pump, yielding means continuously urging said flow-control member into retraction stroke position, a first fluid operable plunger operatively connected with said flow-control member and responsive to fluid pressure acting thereupon to move said flow-control member into full forward stroke position against the thrust of said yielding means, a fluid source for supplying fluid pressure to said first plunger, a second plunger operable by fluid pressure from said fluid source, to move said flow-control member to a restricted forward delivery position, and a third plunger operable by fluid pressure from said fluid source independently of the position of said second plunger and against fluid pressure acting on said first plunger for

shifting said flow-control member to neutral or no-delivery position.

2. In combination with the flow-control member of a reversible variable delivery pump, yielding means continuously urging said flow-control member into full stroke position in one direction, a first fluid operable plunger operable to counteract said yielding means to move said flow-control member into full stroke position in the opposite direction, and a second plunger adapted to stop said flow-control member in said last mentioned position and operable by fluid pressure to counteract said first plunger for positively moving said flow-control member to neutral or no-delivery position.

3. In combination with the flow-control member of a reversible variable delivery pump, yielding means for continuously urging said flow-control member into full stroke position in one direction, a first plunger operable by pressure fluid to counteract said yielding means to move said pump into full stroke position in the opposite direction, a second fluid operable plunger for selectively stopping said flow-control member in said last mentioned full stroke position, said second plunger having an effective area opposed to and larger than the effective area of said first plunger, and means for simultaneously subjecting said two effective areas to fluid pressure for positively moving said flow-control member into an intermediate or neutral position.

4. In combination with the flow-control member of a reversible variable delivery pump, yielding means for continuously urging said flow-control member in one direction into a first full stroke position, a control plunger operatively connected with said flow-control member and operable by pressure fluid to counteract said yielding means for moving said flow-control member into a second full stroke position in the opposite direction, a fluid operable emergency plunger adapted to engage and stop said control plunger when said flow-control member has reached said second full stroke position, said emergency plunger having its effective area opposed to and greater than the effective area of said control plunger, means for admitting pressure fluid simultaneously to said opposed effective areas of said plungers so as to cause said emergency plunger to move said control plunger toward an intermediate position corresponding to the neutral or no-delivery position of said flow-control member, and means for stopping the movement of said control plunger by said emergency plunger when said control plunger has reached said intermediate position.

5. In combination with the flow-control member of a reversible variable delivery pump, yielding means for continuously urging said flow-control member in one direction into a first full stroke position, a first plunger operatively connected with said flow-control member and operable by fluid pressure for moving said flow-control member in the opposite direction through an intermediate position into a second full stroke position against the influence of said yielding means, a second plunger arranged in alignment with said first plunger and movable by pressure fluid from one end position into another end position to move said first plunger into a position between said intermediate position and said second full stroke position, and a third plunger between said first and second plungers and operable by fluid pressure independently of the position of said second plunger to engage said first plunger for moving the same into said intermediate position.

6. In combination with the flow-control member of a reversible variable delivery pump, servo-motor means constantly urging said flow-control member to full retraction stroke position, a first plunger operatively connected with said flow-control member and movable by pressure fluid in one direction to move said flow-control member to full advancing stroke position against said servo-motor means, a second plunger operable by pressure fluid to engage and move said first plunger in the opposite direction against the fluid pressure acting upon said first plunger for shifting said flow-control member into a restricted forward delivery position, and fluid operable emergency means operable independently of the position of said second plunger and responsive to the simultaneous admission of fluid pressure to said first plunger and said emergency means for moving said first plunger into an intermediate position substantially corresponding to no-delivery position of said flow-control member.

7. In combination with the flow-control member of a reversible variable delivery pump, means for continuously urging said flow-control member into full retraction stroke position, a first fluid operable plunger operatively connected with said flow-control member and movable to shift the same into full forward stroke position, a second plunger responsive to the admission of pressure fluid thereto for shifting said flow-control member to a restricted forward position against fluid pressure acting upon said first plunger, a third plunger having an effective area greater than the effective area of said first plunger and reciprocable independently of said second plunger, and means for simultaneously subjecting said first and said second plunger to fluid pressure of the same magnitude for causing said first plunger to shift said flow-control member to an intermediate or substantially no-delivery position.

8. In combination with the flow-control member of a reversible variable delivery pump, resilient means constantly urging said flow-control member into a first full stroke position in one direction, a first plunger operatively connected with said flow-control member and operable by pressure fluid to move said flow-control member in the opposite direction into a second full stroke position through an intermediate or neutral position, a second plunger having a larger diameter than said first plunger but a stroke less than half the stroke of said first plunger, and being operable by pressure fluid to move said flow-control member into a position between said intermediate and said second full stroke position, said second plunger being mounted for engagement with said first plunger, a third fluid operable plunger having a diameter larger than said first plunger and a stroke substantially equaling half the stroke of said first plunger, means associated with said third plunger and arranged for engagement with said first plunger, valve means for selectively admitting pressure fluid to one or more of said plungers for actuating the same, and emergency means operable irrespective of the pressure acting upon said second plunger for subjecting both said first and said third plunger to fluid pressure, to cause movement of said first plunger by said third plunger to said intermediate position, thereby causing said flow-control member to move to and stop at substantially no-delivery position.

9. In combination with the flow-control member of a reversible variable delivery pump, a first

fluid operable piston operatively connected with said flow-control member for moving said flow-control member in one direction into a first full stroke position, yielding means operatively connected with said flow-control member for urging said flow-control member in the opposite direction into a second full stroke position, a second fluid operable piston operable to move said flow control member into a restricted position against fluid pressure acting upon said first piston, means operable to make said yielding means effective, and stop means to stop said first piston in a position corresponding to no-delivery position of said flow-control member when said yielding means has been made effective.

10. In combination with a reciprocable member, servomotor means comprising yielding means continuously urging said reciprocable member into full stroke position in one direction, a reciprocable first plunger operable by fluid pressure to move said reciprocable member into full stroke position in another direction against the thrust of said yielding means, a reciprocable second plunger operable by fluid pressure to move said reciprocable member to a restricted stroke position against the fluid pressure acting upon said first plunger, and a third reciprocable plunger operable by fluid pressure to move said reciprocable member into an intermediate or neutral position against fluid pressure acting upon said first plunger and irrespective of fluid pressure acting upon said second plunger.

11. In combination with a reciprocable member, yielding means continuously urging said reciprocable member in one direction into a first full stroke position, a plunger operatively connected with said reciprocable member and operable by pressure fluid for moving said reciprocable member against the thrust of said yielding means into a second full stroke position, fluid pressure operable stop means movable selectively into stopping position for stopping said plunger in a predetermined position between said two full stroke positions, means normally holding said stop means in ineffective position, and emergency means operable to control the supply of pressure fluid to said

plunger and said stop means to cause said yielding means to move said reciprocable member away from said second full stroke position while simultaneously causing said stop means to move into said stopping position to prevent said yielding means from moving said reciprocable member beyond said predetermined position.

12. In combination with a reciprocable member, yielding means continuously urging said reciprocable member in one direction into a first full stroke position, a first plunger operatively connected with said reciprocable member and operable by pressure fluid for moving said reciprocable member against the thrust of said yielding means into a second full stroke position, stop means for stopping said reciprocable member in an intermediate or neutral position against the thrust of said yielding means, a second plunger operable by fluid pressure to move said reciprocable member 20 into a position between said intermediate and said second full stroke positions, valve means movable selectively into closed position for admitting pressure fluid to said first plunger for actuating the same or into open position for exhausting fluid from said first plunger, and means responsive to movement of said valve means to open position for making said stop means effective.

13. In combination with a reciprocable member, yielding means continuously urging said reciprocable member in one direction into a first full stroke position, a plunger operatively connected with said reciprocable member and operable by pressure fluid for moving said reciprocable member against the thrust of said yielding means into a second full stroke position, valve means movable selectively into closed position for admitting pressure fluid to said plunger for actuating the same or into open position for exhausting fluid from said plunger, and fluid operable stop means operable selectively to stop said reciprocable member in a position intermediate said two full stroke positions in response to movement of said valve means into open position.
